(57) **CLAIM**

The ornamental design for a dog car seat, as shown and described.

DESCRIPTION

FIG. 1 is a front perspective view of a dog car seat, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The thin broken lines in the drawings illustrate the portions of the dog car seat, which form no part of the claimed design. The circular features shown in thin broken lines in FIG. 7 illustrate portions of the dog car seat that form no part of the claimed design. The remaining broken lines represent stitching which is part of the claimed design.
